CLAIM

(52) U.S. Cl.

The ornamental design for a cushion assembly for breathing mask assembly, as shown and described.

USPC **D24/110.4**

DESCRIPTION

(58) **Field of Classification Search**

USPC D24/110–110.4, 110.6, 127; D29/108, D29/122; D32/21, 22, 23, 24, 31, 32, 33

CPC A61M 16/0622; A61M 16/0616; A61M 16/0633; A61M 16/06; A61M 16/0683; A61M 16/0605; A61M 16/0644

FIG. 1 is a front, top, and side perspective view of a cushion assembly for breathing mask assembly embodying our new design;

FIG. 2 is a rear, top, and side perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof; and,

FIG. 9 is a cross-sectional view taken along line 9-9 of FIG.

See application file for complete search history.

3.

Broken lines are used to illustrate portions of the cushion

assembly for breathing mask assembly that form no part of

the claimed design.
